TROLLEY EAR

Samuel S. Matthes, Mansfield, Ohio, assignor to
The Ohio Brass Company, Mansfield, Ohio, a
corporation of New Jersey

Application May 29, 1943, Serial No. 489,248

9 Claims. (Cl. 191—43)

My invention relates to devices for supporting conductors and more commonly referred to as trolley ears.

My invention is an improvement upon my previous trolley ear described and illustrated in Patent 2,027,604 issued January 14, 1936.

One object of my invention is to provide an ear of two parts, one of which is of cast metal, and in which the two parts are securely interlocked and capable of withstanding the stresses thereon, in service especially strains due to the side pull of the trolley wire and the wear upon the lips.

Another object of my invention is to provide an ear in which the wire holder or body for the trolley wire may be of different metal from that of the support for the holder, and which may be produced economically and which is practical to construct.

In the past the great majority of trolley ears have been entirely of cast metal in one piece.

These have and are giving general satisfaction but there are conditions under which such an ear does not give maximum performance, and it has been found that by making the wire holder of a different metal from that of the support, improved results are secured. Trolley ears have been made in the past of two different metals, as for instance, the wire holder of rolled or drawn sheet metal, such as copper and the support of a casting, usually a non-ferrous alloy.

In my improved ear I produce the holder preferably of sheet copper, however this may be of other metal such as brass, bronze or even soft steel. Various metals in sheet form are procurable and are easily formed to various shapes by means of forming dies. While such dies are initially expensive, their life is usually great and the cost is soon absorbed in quantity production, thus producing a relatively economical product and much more uniform than by casting.

I find that the support may be cast from a considerably cheaper alloy when the wire holder is formed from sheet metal and secured to the holder of sheet metal than when the entire ear is cast in one piece because in the latter case it is necessary to use an alloy which is first suitable for the holder and this requires a more expensive alloy than necessary for the support. An ear in which both parts are cast and one part cast onto the other is disclosed in Patent 1,516,864 issued November 25, 1924.

The holder is so constructed that the support may be attached thereto by casting at the time the support is cast. This produces a secure in-

terlock between the wire holder and support part, especially with proper construction of the holder.

My invention will be best understood from the following drawing, and the description thereof, both forming parts of this application.

In the drawing:

Fig. 1 is a side view in partial section of my invention.

Fig. 2 is an enlarged end view of Fig. 1.

Fig. 3 is an enlarged section on line 3—3 of Fig. 1.

Fig. 4 is a top view of the wire holder portion of Fig. 1 after forming but before assembling.

Fig. 5 is a side view of the holder of Fig. 1 after forming but before assembling.

Fig. 6 is an enlarged section on the line 6—6 of Fig. 5, with a trolley wire dotted in.

I first produce the runner 1 from sheet metal and cut to the proper size to fit the trolley wire for which the ear is intended. I then drill the several holes 2 but which may be produced by stamping in which case they may be square, oblong or of other suitable shape.

I then form, by suitable dies, the drilled sheet 25 into a U-shaped member having a channel or groove 3 of proper size and shape to fit the trolley wire. The depending sides or lips 4 are adapted to be peened about the wire to hold it in place.

At the time of forming the metal sheet and producing the channel 3 I form an up-struck portion or elongated portion 5 which forms a second groove 6 opening into the channel 3 with which the openings 2 communicate.

The ends of the holder or body, for a limited 35 distance back from the ends thereof are formed with a bight connecting the lips, the curvature of the bight made to conform to and fit the trolley wire.

When a trolley wire is placed in the groove 3 of the holder just after forming, the groove 6 forms a receptacle with the openings 2.

The support 7 for the holder 1 is of cast metal and cast to the holder at the same time the support is cast. This operation is preferably done 45 in dies, the process being known as die-casting.

The wire holder as shown in Figs. 2 and 3 is placed in a proper recess in the die and a core shaped to the slot 3 is inserted in the slot. This provides the receptacle formed by the groove 6 referred to above.

The openings 12 communicate with the groove 6 and with a recess in the casting die which conforms to the desired shape of the support 7.

Molten metal is now forced into the die under 55 pressure, filling the cavity for the support 7 and

also flowing through the openings 2 and into the receptacle formed by the groove 6.

When the device is removed from the casting die, it will be found that the two parts 1 and 7 are securely interlocked and particularly against side strain of the trolley wire at curves.

The elongated groove 6 is filled with the cast metal which forms a continuous bar 8 and the cast metal in the openings 2 is integrally united to the portion 8 and to the support 7 and this construction forms an unusually strong interlock, and any stresses in service are uniformly distributed along the ears.

The inner surface of the portion 8 conforms to the curvature of the trolley wire and offers a backing therefor against upward pressure from a passing current collector.

The boss 9 is usually threaded to receive a hanger support.

After the ear is received from the casting die, the ends of the lips 4 are tapered to ease and make smooth the passage of the current collector onto and off the ear.

The wire holder may be formed by casting, but I prefer to make it of drawn or rolled sheet metal.

The groove 6 may be broken up into several sections in place of a single continuous groove.

Having described my invention I claim for the same as follows:

1. A conductor support comprising an elongated metal body having spaced lips forming a groove to receive a trolley wire and connected at each end by a bight, the bights for a limited distance from each end of the body conforming in shape and size to the trolley wire, the portion of the body between said bights being raised with respect to the said limited portions whereby the inner surface of said raised portion is spaced from a longitudinal plane coinciding with the inner surface of said bights whereby a continuous channel is formed within said body by said raised portion, a plurality of openings extending through the body along the said raised portion and communicating with the said channel, the openings being of less width than that of the channel opening and a metal support secured to said raised portion by casting the support along the outer surface of said raised portion and throughout the entire length of said channel and integrally united by cast metal extending through said openings.

2. A conductor support comprising an elongated metal body having spaced lips forming a two-part groove with one part to receive a trolley wire and connected at each end by a bight, the bights for a limited distance from each end of the body conforming in shape and size to the trolley wire, the portion of the body between said limited portions being raised with respect to the said bights whereby the other part of said groove is formed with the inner surface of said raised portion spaced from a plane coinciding with the inner surface of said bights, the said other part comprising an elongated channel within said body, a plurality of openings extending through the body along the said raised portion and communicating with the said channel and a metal support secured to said raised portion by casting the support along the outer surface of said raised portion and throughout the entire length of said longitudinal channel within said body and through said openings, the exposed surface of said cast metal within the channel corresponding in size and curvature to that of the trolley wire.

3. A trolley wire support comprising, in combination, an inverted U shaped body having

spaced lips and so shaped as to form a groove therebetween having two parallel portions, one portion to receive a trolley wire, the ends of said lips connected by bights, each bight having a surface conforming to the curvature of the trolley wire, the other portion of said groove extending between the inner ends of the bights and forming a single continuous longitudinal channel opening into the said one portion of the groove, openings extending through the metal forming the wall of the channel and communicating with the channel, a metal support interlocked with the portion of the body forming the said other part of the groove by casting along the outer surface of said body portion and by filling said channel with said cast metal thereby forming a continuous bar and filling said openings with cast metal whereby said external portion of said support is integrally connected to said continuous bar in said channel.

20 4. A trolley wire device comprising, in combination, an inverted U shaped body having spaced lips forming a groove therebetween to receive a trolley wire, the ends of said lips connected by bights, each bight having a surface conforming to the curvature of the trolley wire surface, the body portion between the bights up-thrust to form a longitudinal channel within the U shaped body and closed at its ends by the said bights and opening into its groove throughout the length, openings through the raised wall of the channel, cast metal filling the channel throughout its length and forming a support for the body portion, cast metal forming a support for the cast metal support within the channel extending along the exterior surface of the wall forming the channel and provided with means to attach the device to a support, and cast metal extending through the openings and integral with the aforesaid cast metal portions whereby the portions are secured to the body.

5. A trolley wire device comprising, in combination, a body member formed from sheet metal and having a pair of spaced bendable lips forming a two part groove, one part extending for the entire length of the body to receive a trolley wire, the lips connected at each end by a bight of limited length along the body and conforming to the curvature of the wire, the other part of the groove extending between the inner ends of the bights and opening throughout its length into the said one part of the groove, openings through the wall of the said other part of the groove, a support member for said body interlocked thereto by casting the same with said body to extend along the outer surface of the wall of said second part of the groove and to fill said openings and said second part of the groove whereby the body member is supported by the metal in said second part of the groove which in turn is supported by the exterior portion of the support through the medium of the portions in said openings.

6. A conductor supporting device comprising a conductor holder provided with a two part longitudinal groove, one part larger than the other part to receive and hold the conductor and means extending through the wall of the holder forming the said other part of the groove, a support member cast with a portion extending along the exterior surface of the holder and a portion filling the said other part of the groove within the body to support the said holder and other portions extending through the said means and interlocking the first two said portions of the holder to form a unitary device.

7. In combination, a trolley wire, a conductor holder positioned on said wire, the holder provided with lips bent onto the wire and having up-thrust means forming grooved means within the holder disposed along the trolley wire for substantially the entire length of the holder, openings through the wall of said up-thrust means and opening into said grooved means, a support for said holder formed of cast metal and attached to said holder by casting said metal along the outer surface of said up-thrust portion, through said openings and within said grooved means, the metal in said grooved means forming supporting means for said holder and a backing for said trolley wire against the up-thrust of a passing current collector.

8. A conductor supporting device comprising, in combination, a holder provided with a longitudinal channel to receive and hold a trolley wire, auxiliary channel means within the holder and disposed along the holder, cast metal positioned within the said auxiliary channel means to support the holder, a support for the said metal in

the channel means within the holder formed of cast metal extending along the outer wall of said holder, openings through the wall of said holder, and cast metal filling said openings and integrally uniting to the aforesaid cast metal parts whereby the cast metal in the channel means is interlocked to the holder.

9. A conductor holder for a conductor support comprising, in combination, an elongated body of sheet metal formed into a channel having a U shaped groove to receive a trolley wire of extended length, the depending sides of the channel forming lips bendable about the wire, the lips for a distance extending back from the ends thereof being connected by a bight shaped and sized to the trolley wire, a second groove paralleling the first groove and extending between the inner ends of the bights, the second groove opening for its entire length into the first groove and openings extending through the wall of the body into the said second groove.
